UNITED STATES PATENT OFFICE.

HENRY H. WAINWRIGHT, OF PHILADELPHIA, PENNSYLVANIA.

No. 848,075.

Specification of Letters Patent.

Patented March 26, 1907.

Application filed February 7, 1906. Serial No. 299,879.

To all whom it may concern:

Be it known that I, HENRY H. WAINWRIGHT, a citizen of the United States of America, and a resident of the city of Philadelphia, in the State of Pennsylvania, have invented certain new and useful Improvements in Metal Nosings for Concrete Steps and other Structures, of which the following is a specification.

10 This invention relates to improvements in metal nosings for concrete steps and other structures.

The object of the invention is the protection of the exposed portions of concrete structures—such as steps, platforms, and other structures—by metal plates, of novel shape, which are termed "nosings" and are anchored or secured in the concrete by anchoring devices integral with or fixed on the 20 body of the plates.

The invention also provides for combining with the nosings strips of rubber, leather, or other non-slipping materials whenever necessary, as in the case of steps, to provide secure 25 foothold, the nosings being provided in such cases with means, as will be hereinafter described, for securely holding such strips in position.

Since the essentials of the invention can be 30 embodied in various forms, I illustrate several modifications thereof in the accompanying drawings as examples of various structures which embody the invention.

Referring to the said drawings to aid the 35 description, Figure 1 is a perspective view of a block of concrete such as would constitute a platform equipped with one form of the invention. Fig. 2 is a perspective view of part of a flight of steps provided with another 40 form of the invention equipped with non-slipping strips. Fig. 3 is a perspective view of a single concrete step provided with another form of the invention, and also equipped with non-slipping strips. Fig. 4 is 45 a perspective view of a concrete step provided with still another form of the invention, and also equipped with non-slipping strips.

Referring to Fig. 1, the exposed edge of 50 the concrete mass A, which constitutes a platform, step, or similar structure, is protected from the wear due to ordinary use, as well as from breakage by the blows of heavy bodies against the concrete by a nosing 55 which is formed of any suitable metal, as steel, by rolling or in any other suitable

manner. Said nosing comprises the curved corner 1, (which preferably projects somewhat beyond the vertical face of the concrete A, as shown,) the flat body 2, and the anchor 3 4, which is integral with or firmly fastened to said body 2. Said body 2 projects horizontally back from said corner 1 flush with the surface of the concrete mass, and said anchor consists of a web 3 substantially perpendicular to the body 2, which enters into the concrete mass and is preferably provided with a head 4, which forms a locking device. In the form of nosing shown in Fig. 1 the corner 1 is preferably provided with the downwardly-extending tongue or flange 5, as shown. Said nosing preferably extends the entire length of the exposed face of the concrete, and said web 3 and head 4 is also preferably continuous the entire length of the 75 nosing; but said web or head, one or both, may be interrupted or cut away at various points, and said head 4 may have different shape from that shown. The nosing is temporarily supported in any suitable manner in 80 the mold in which the concrete mass is formed, the soft wet concrete being then poured and rammed in. When the concrete has set, the nosing will be firmly held to the concrete by the rusting between the concrete 85 and the metal, as fully explained in my United States Letters Patent numbered 578,668, dated March 9, 1897, and the security of said nosing in the concrete is further increased by said head 4, which firmly locks 90 said nosing to the concrete mass.

In Fig. 2, which shows the preferred form of the invention for steps and like constructions, the metal nosing, which is preferably molded into the concrete mass in the manner 95 hereinbefore described, has a corner 8, which is substantially a semicircle and with beveled edge 14, a broad flat rearwardly-extending body or tread 9, and an anchor comprising the substantially perpendicular web 10, 100 which enters the concrete mass, and the double-locking head 11, and I further increase the utility of the invention by providing the said tread 9 with undercut grooves to securely hold non-slipping strips 12, of rubber, 105 leather, or other material, which will insure secure footing to one descending the steps. Said corner 8 will of course preferably extend the entire length of the concrete step B, and the web 10 and head 11 will preferably, but 110 not necessarily, be continuous the entire length of said nosing.

In Fig. 3 I show a form of nosing for a concrete step or other structure wherein the corner 16 is substantially a quarter-circle, and the tread 17 and anchor 18 19 are respectively similar to corresponding parts in Fig. 1; but the tread 17 is provided with undercut grooves for strips of non-slipping material 20.

In Fig. 4 I show a nosing for concrete steps and other structures having a grooved tread 23, provided with non-slipping strips 26 and an anchor 24 25, which are similar respectively to corresponding parts in Fig. 1; but in place of the round corner 1 there is a flat bar or web 22 flush with and protecting the exposed face of the concrete mass D, while the tread 23 protects the exposed upper surface thereof.

Now, having described my improvements, I claim as my invention—

1. A nosing for concrete steps and platforms consisting of the following members combined in one integral metal structure, viz. a body-plate adapted to protect the top of the concrete, a longitudinal corner-bar adapted to protect the top and front of the concrete, a longitudinal web adapted to enter the concrete mass at substantially right angles to said body-plate, and a head thereof adapted to anchor the nosing firmly to the concrete, substantially as described.

2. A nosing for concrete steps and platforms consisting of the following members

combined in one integral metal structure, viz. a body-plate adapted to protect the upper surface of the concrete and provided with grooves adapted to receive strips of suitable material, a longitudinal corner-bar adapted to protect the top and front of the concrete, a longitudinal web adapted to enter the concrete mass at substantially right angles to said body-plate, and a head thereof adapted to anchor the nosing firmly to the concrete, substantially as described.

3. A nosing for concrete steps and platforms consisting of the following members combined in one integral metal structure, viz. a body-plate adapted to protect the upper surface of the concrete and provided with grooves adapted to receive strips of suitable material, a longitudinal corner-bar adapted to protect the top and front of the concrete, a longitudinal web adapted to enter the concrete mass at substantially right angles to said body-plate, and a head thereof adapted to anchor the nosing firmly to the concrete, combined with strips of non-slipping material in said grooves of the body-plate, substantially as described.

Signed at Philadelphia this 5th day of February, 1906.

HENRY H. WAINWRIGHT.
